UNITED STATES PATENT OFFICE.

EMIL BENTE AND PAUL STUHLMANN, OF BARMEN, GERMANY, ASSIGNEES TO MAX HENKELS, OF NEW YORK, N. Y.

LACE WITH NET OR TULLE-LIKE GROUNDWORK.

Application filed December 27, 1922. Serial No. 609,269.

To all whom it may concern:

Be it known that we, EMIL BENTE and PAUL STUHLMANN, citizens of the German Empire, residing at Barmen, Germany, have 5 invented certain new and useful Improvements in Laces with Net or Tulle-Like Groundwork, of which the following is a specification.

This invention relates to the production 10 of lace with tulle-like ground work. The object of the invention is to make the manufacture more simple, rapid and economical and to obtain with a very small number of threads a pleasant looking and firmly braided lace which retains its design and will 15 resist distortion. With this and other objects in view, the present method of producing lace with tulle-like ground work consists in warp-like spaced pillars of but two threads, 20 each pillar consisting of a lightly tensioned thread and a second more heavily tensioned thread, both twisted together, to form the pillar, and in connecting said spaced pillars by reciprocatively interchanging the lighter tensioned threads of the pillars so as to 25 form pairs of transversal bars, and by crossing each transversal bar over the other so as to interlock with the heavier tensioned threads of the warp-pillars.

30 In the modification of this method the transversal bars are crossed over each other at different places the crossing points being located in the warp-pillars proper, and the other crossing points being in the space between two adjacent pillars.

On making our new lace on the single-thread lace braiding machine the bobbin-carriers of the latter are almost continuously in motion; especially during the producing of the ground-work only a few bobbin-carriers are to be arrested for short intervals, the working is therefore rapid and economical. Furthermore our new lace requires only a small quantity of threads; and 45 as even the tension of those threads which are somewhat more heavily tensioned than others, is still rather slight, the new lace can be manufactured from comparatively weak and consequently cheap thread material.

We now proceed to more fully explain our new lace and the process of making the same, reference being made to the annexed drawing illustrating by way of example two

embodiments of our lace, and in which we 55 show in

Fig. 1 a piece of lace on a greatly enlarged scale;

Fig. 2 the ways of the bobbins in producing the lace illustrated in Fig. 1 on the single-thread lace-braiding machine,

Fig. 3 a piece of a second lace, also on a greatly enlarged scale.

In the example shown in Fig. 1, the ground-work of the lace is composed of a 65 series of warp-like longitudinal strips 1 to 8, each strip being formed by twisting together a slightly tensioned thread *a* and a somewhat more heavily tensioned thread *b*. For clearness the slightly tensioned threads 70 are marked by fine strokes of the pen, the heavily tensioned threads, on the contrary, by bold strokes. The strips or pillars 1 to 75 8 are connected by means of weft-like transversal staves or bars *c* which are formed by interchanging the slightly tensioned threads *a*, *a* of two adjacent longitudinal strips and simultaneously crossing said threads. To lock the staves or spokes in their correct positions, the crossing points of the interchanged threads *a*, *a* are embraced by the 80 heavily tensioned thread *b* of one of the two adjacent strips and thereby drawn into the respective longitudinal strip. Thus each pair of threads *a*, *a* at the place of exchange 85 resembles a loop formed by one thread only, but in fact each stave or spoke consists of two threads. From this a great durability of the lace results. Should any of the threads forming a stave or spoke *c* break, 90 the longitudinal strips are still maintained in their correct distance by the aid of the remaining thread. In consequence of the fact that every following exchange of the slightly tensioned threads takes place between another pair of longitudinal strips than the proceeding one, the threads *a*, *a* have a stepped run alternately in the one diagonal direction and in the other from one edge of the lace to the opposite edge and vice versa. 95 Therefore, all threads *a*, *a* extend not only over the entire length, but also over the entire width of the lace, as a result of which the firmness and durability of the lace is 100 once more considerably increased.

To make the ground-work illustrated in Fig. 1 on the single-thread lace-braiding machine, the bobbin-carriers *a*, *b*, are ar- 105

ranged on the plates of the machine in such a manner that each carrier a_x carrying a bobbin with heavily tensioned thread is followed by a carrier b_x having a bobbin with 5 slightly tensioned thread on it. See left-hand part of Fig. 2 in which the first named bobbin carriers are marked by black points, the last named, on the contrary, by small circles. The ways of the bobbin-carriers are 10 shown in the right-hand part of Fig. 2, wherein the spaces between the straight horizontal auxiliary lines correspond to the plates, whereas the spaces between the straight vertical auxiliary lines each correspond 15 to one half revolution of the drivers. The diagonal fine and bold strokes of the pen illustrate the movements of the respective bobbin-carriers on one and the same plate or their transfer from one plate to 20 another, while the horizontal fine and bold strokes mean arresting of the respective bobbin-carriers. As is evident from an inspection of Fig. 2, the bobbin carriers are almost continuously in motion; only during 25 the interchange of the slightly tensioned threads between adjacent longitudinal strips some of those bobbin-carriers carrying a bobbin with heavily tensioned thread are arrested for a short time.

30 The net or tulle-like ground-work above described can be provided with any desired pattern, and what is more, not only the patterns ordinarily applied to tulle lace but, besides or instead of these patterns also 35 the peculiar patterns of the real or hand-braided lace, for example tufts, spiders, leaf-like figures etc. can be worked into the ground-work, thus making our new lace particularly valuable. To the lace shown 40 by way of example in Fig. 1, a tuft d is applied. Said tuft is formed by means of two heavily tensioned threads b^1, b^2 and of two slightly tensioned threads a^1, a^2 all taken from those longitudinal strips which 45 are interrupted by the provision of the pattern. Whereas the two heavily tensioned threads b^1, b^2 are led straight through in the longitudinal direction of the lace, one of the slightly tensioned threads, a^1 , runs continuously to and fro between said two threads b^1 and b^2 , and embraces the latter at each of its return places. At the same time the thread a^1 running to and fro is in 50 a web-like texture interlaced with the other slightly tensioned thread a^2 which is conducted through the tuft in the longitudinal direction, whereby the thread a^1 is locked in its respective positions. As shown, the tuft d is preferably placed in a square frame 55 standing on one of its corners and formed 60 by four diagonally arranged strips $4^a, 5^a, 2^a$ and 7^a .

In the lace shown in Fig. 3 a simple pattern is worked in by frequently interchanging 65 the slightly tensioned threads a, a of

two immediately adjacent strips, for example, of the strips 4 and 5. In connection therewith the crossing points of the slightly tensioned threads may, similar to Fig. 1, be drawn into one of the two adjacent strips 70 as to resemble loop-like staves or spokes i , or the interchanged threads may be crossed in the space between the strips 4 and 5, as shown at h . Of course, also to this lace spiders, tufts, leaf-like figures and other 75 patterns usual in the hand-made lace and producible on the single-thread lace-braiding machine may be applied.

Finally the lace shown in Fig. 3 is provided with strengthened edges. These edges 80 are formed by a continuous interchange of the threads a, a between the longitudinal strips 1 and 2, and 7 and 8, respectively, and by crossing said threads in the space between the adjacent strips, while the latter 85 are simultaneously drawn together so tightly as to resemble in the finished fabric a common longitudinal strip. At the same time, there may be produced some sort of picots 90 at the edges of the lace by leading some of the slightly tensioned threads a, a out from the marginal strips and back into the latter so as to form the loops m, m .

We wish it to be stated that our invention is not limited to the examples shown on the drawings, for many other embodiments may suggest themselves to those skilled in the art, without departing from the spirit of the invention as pointed out in the following claims.

Claims:

1. The method of producing lace with tulle-like ground work which consists in forming warp-like spaced pillars of but two threads, each pillar consisting of a lightly tensioned thread and a second heavily tensioned thread, both twisted together to form the pillar, and in connecting said spaced pillars by reciprocatively interchanging the lighter tensioned threads of the pillars so as 105 to form pairs of transversal bars, and by crossing each transversal bar over the other so as to interlock with the heavier tensioned threads of the warp-pillars.

2. The method of producing lace with 115 tulle-like ground work which consists in forming warp-like spaced pillars of but two threads, each pillar consisting of a lightly tensioned thread and a second heavily tensioned thread, both twisted together to form 120 the pillar, and in connecting said spaced pillars by reciprocatively interchanging the lighter tensioned threads of the pillars so as to form pairs of transversal bars, and by crossing each transversal bar over the other, 125 locating the crossing points in the warp-like pillars and also in the space between two adjacent pillars.

3. A lace with tulle-like ground work having warp-like spaced pillars of but two 130

threads, each pillar consisting of a single lightly tensioned thread and a second heavier tensioned thread, twisted together to form the pillar and having transversal bars connecting said spaced pillars, these bars having interchanged threads, crossing each other so as to interlock with the heavier tensioned threads of the pillars at the crossing points.

4. A lace with tulle-like ground work having spaced longitudinal warp-like pillars of but two threads, and having transversal bars connecting said spaced warp-like pillars,

said bars having interchanged threads crossing each other, the crossing points being located in the warp-pillars proper and also 15 in the space between adjacent pillars.

In testimony whereof we affix our signatures in presence of two witnesses.

EMIL BENTE,
PAUL STUHLMANN.
